CAN CLOSURE AND METHOD OF
FORMING SAME

Philip F. Catalano and Anthony Grabowski, Chicago, Ill.,
assignors to Continental Can Company, Inc., New York,
N.Y., a corporation of New York

Filed June 6, 1962, Ser. No. 200,534
16 Claims. (Cl. 220—67)

The invention relates generally to the art of can making and resides in the provision of a novel can closure and method of forming the same, while the invention is applicable to the manufacture of cans wherein the bodies are of seamless, drawn type, it preferably is applied in the manufacture of cans including bodies of steel, aluminum or aluminum alloys having very thin walls, say of 0.004 to 0.011 inch, for example, and including welded side seams wherein the thickness of the metal at the weld corresponds generally to the thickness of the metal elsewhere in the body.

In the manufacture of cans, it is common practice to secure metal closures on the metal bodies by the well known double rolled seaming action, edge portions of each can body and its closure being rolled together in the formation of the double seam. In this conventional practice each can body is provided with outwardly turned flanges at its end extremities, and each closure includes a central countersink presenting a chuck wall which is insertable into an end of the can body, and an outwardly extending portion for overlying a body flange and adapted to be rolled with the body flange into the sealing seam structure. The bodies commonly have lock and lap side seams the lock portions of which are composed of interlocked body hooks, thus presenting four thicknesses of metal, and the lap portions of which are disposed at the ends of the side seam and present two thicknesses of metal which are rolled into the sealing seam structure.

Conventional side seam structures of the character stated usually are solder bonded, and since the flanging of the bodies is accomplished after the solder bonding, the flanging operation often results in a rupturing of the bond in the lap seam portions intended to be rolled into the closure seam structures, and leaky cans are thus formed. It sometimes happens also that by reason of the turning of non-uniform lengths of the body metal in the flanging operation, or in the chucking of the bodies incidental to the formation of closure seams, cans of non-uniform height will be provided. Also, when attempts have been made to form flanged can bodies from thin stock, such as double rolled tin plate, difficulties such as rupturing and leakage have been encountered because this stock cannot be flanged satisfactorily, the flanges having what is known in the industry as H-grain and circumferential brittleness.

A primary object of the present invention is to avoid the problems above referred to and provide a novel can closure wherein interlocking side seams and the rolling together of closure and body edge portions is entirely eliminated, thus providing for a marked saving of metal as a result of the elimination of body flanges and interlocked side seams, without sacrifice in the objective of providing wholly practical closure seals, even against egress of relatively high pressures from within the sealed cans.

Another object of the invention is to provide a novel closure of the character stated wherein the closure seal may embody a sealing compound, or optionally, a metal-to-metal adhesive bond, providing not only for the desired sealing purpose but also adding to the structural strength in the finished seam.

A further object of the invention is to provide a novel

2

closure of the character stated wherein provision is made for adding rigidity to the seam, providing a greater strength against relatively high sealed-in pressures, and also facilitating application of the closure piercing types of can openers, by reason of the inclusion in the closure of an opener engaging ledge of practical dimension and strength.

Another object of the invention is to provide a closure of the character stated in which the can body is devoid of an outwardly turned flange and has a generally cylindrical end extremity over which the annular channel of an end closure is receivable and which merges downwardly into an inwardly turned bead presenting a horizontal seat or shoulder merging inwardly and downwardly into an outwardly and downwardly flared and curving wall portion finally merging into the main upright body wall of the can body.

Still another object of the invention is to provide a can body of the character stated wherein the body structure is the same at each of its ends, is not only devoid of outwardly turned end flanges but also is either seamless or provided with a side seam which does not depart substantially from the thickness of the metal of the body wall stock, and wherein the main body between its curving end portion flares is circumferentially corrugated uniformly throughout its height for providing form and internal pressure retaining rigidity.

A further object of the invention is to provide a novel closure of the character stated wherein the can body is formed in the manner hereinabove stressed and in which the can end closure includes a central closure portion surrounded by an upstanding downwardly opening channel defined by an inner chuck wall connected with the central closure portion through a chuck radius and an outer skirt or seaming wall which is longer than the generally cylindrical end extremity of the body and which is connected with the chuck wall through a channel radius, said central closure portion firmly resting on the horizontal shoulder of the body about an annulus joining with the chuck wall through said chuck radius, and the seaming wall portion remote from the channel radius being turned snugly under and locked against the body at said shoulder with the generally cylindrical body end extremity tightly embraced between the chuck wall and the seaming wall and conforming in shape thereto and with the channel radius firmly engaged over the end edge extremity of said generally cylindrical body end extremity.

A still further object of the invention is to provide a novel can closure of the character stated wherein the closure seam is sealed by a sealing medium in the closure channel and engaging between the opposing faces of the generally cylindrical body end extremity, the chuck wall and the seaming wall.

Still another object of the invention is to provide a novel can closure of the character stated wherein the closure seam is sealed by a seam bonding adhesive in the closure channel and engaging between the opposing faces of the generally cylindrical body end extremity, the chuck wall and the seaming wall.

A further object of the invention is to provide a novel can closure of the character stated wherein the end closure seaming wall portion remote from the channel radius carries an outwardly turned reinforcing hem which is engaged in shape conforming closure locking contact under the horizontal shoulder on the body.

Still another object of the invention is to provide a novel can closure of the character stated wherein the end closure seaming wall portion remote from the channel radius carries an inwardly turned reinforcing hem which is engaged in shape conforming closure locking contact under the horizontal shoulder on the body.

A further object of the invention is to provide a novel method of forming an end closure for a metal can having a body devoid of a flange at its end extremity, said extremity terminating in a generally cylindrical portion merging downwardly into an inwardly turned bead presenting a horizontal shoulder merging inwardly and downwardly into an outwardly flared portion, with a closure having a central closure portion surrounded by an upstanding downwardly opening channel defined by an inner chuck wall connected with the central closure portion through a chuck radius and an outer seaming wall connected with the chuck wall through a channel radius; said method comprising placing the closure over the body end extremity with the chuck wall closely telescoped within said end extremity and the central closure portion firmly seated on the horizontal shoulder, and turning the seaming wall portion remote from the channel radius under and against the body at the horizontal shoulder to lock the channel firmly over the body end extremity and pressing the chuck wall and the seaming wall into sealing and shape conforming contact against opposite sides of the body end extremity while conforming the turned seaming wall portion to the body at and adjacent to the horizontal shoulder engaged thereby.

Another object of the invention is to provide a method of the character stated including the provision on the closure seaming wall portion remote from the channel radius of a reinforcing hem and the reshaping of the hem against the body at and adjacent the horizontal shoulder during the securing and locking of the closure on the body.

A further object of the invention is to provide a can closing and sealing method of the character stated including the step of sealing the closure seam by provision of a sealing medium engaging between the opposing faces of the generally cylindrical body end extremity, the chuck wall and the seaming wall.

A still further object of the invention is to provide a can closing and sealing method of the character stated including the step of sealing the closure seam by provision of a seam bonding adhesive engaging between the opposing faces of the generally cylindrical body end extremity, the chuck wall and the seaming wall.

With the above and other objects in view that will hereinafter appear, the nature of the invention will be more clearly understood by reference to the following detailed description, the appended claims and the several views illustrated in the accompanying drawings.

In the drawings:

FIGURE 1 is a side elevation illustrating a complete can formed in accordance with the invention, top and bottom end closures being affixed thereon.

FIGURE 2 is an enlarged fragmentary vertical cross section through one side wall of the can body, the bottom of the can body being confined on a supporting bed plate and a top end closure being initially applied over the generally, cylindrical upper end extremity of the body being dropped onto the can body and resting on the horizontal seat shoulder provided thereon.

FIGURE 3 is an enlarged fragmentary sectional view illustrating the second stage of the securing of the end closure shown initially applied in FIGURE 2, the application of the chuck and the seaming roll conforming the seam chuck wall and the seaming roll of the closure to shape with the end extremity of the body wall tightly conformed between them, the lower, inwardly hemmed extremity of the seaming wall being initially contacted with the body in the process of being locked under and conformed to the body shoulder and the portions thereof adjacent.

FIGURE 4 is a view similar to FIGURE 3 and illustrating the completion of the locking-on of the cover and the reshaping of the inwardly directed reinforcing hem thereof.

FIGURE 5 is a fragmentary sectional view illustrating

the interlocking chuck and seaming roll and the completion of the closure seam therebetween.

FIGURE 6 is a fragmentary sectional view of a plurality of can end closures of the form shown in FIGURES 2 through 5, said closures being shown in nested, stacked relation.

FIGURE 7 is a fragmentary sectional view corresponding to the initial closure mounting illustrated in FIGURE 2 and showing a modified form of closure including an outwardly and upwardly directed edge curl.

FIGURE 8 is a fragmentary sectional view similar to FIGURE 3 and illustrating the seam conformation between the chuck and the seaming roll and the initial reshaping of the cover edge curl into an open, outwardly directed hem.

FIGURE 9 is a fragmentary sectional view similar to FIGURE 4 and illustrating the completion of the locking on of the cover and the reshaping of the outwardly directed reinforcing hem thereof.

FIGURE 10 is a fragmentary sectional view similar to FIGURE 6 and illustrating can ends of the form shown in FIGURES 7, 8 and 9 in nested, stacked relation.

In the example of embodiment of the invention herein disclosed, the improved closures are provided on an improved can body best shown in FIGURES 1 and 2. The body generally designated 5, as shown in FIGURE 1, has top and bottom end closures respectively designated 6 and 7 applied thereon. At each body end extremity, there is provided a generally cylindrical portion 8 presenting an edge extremity 9, upwardly or downwardly as the case may be. Each generally cylindrical portion 8 merges through an inturned bead 10 with a horizontal seat or locking shoulder 11, and each such horizontal seat or shoulder merges through an inwardly, downwardly and then outwardly turned portion 12 into an outwardly curved body flare 13 which in turn merges at 14 into the main body portion of the can body generally designated 5. Between the outwardly curving flares 13, the main body is uniformly and circumferentially corrugated to give to the very thin wall structure of 0.004" to 0.011" thickness the desired rigidity and strength for retaining sealed-in pressures for which the can is designed.

The ends or covers for use in the form of the invention shown in FIGURES 2 through 5 are illustrated in nested, stacked relation in FIGURE 6. Each such can end or closure includes a central closure portion 11 and a surrounding upstanding and downwardly opening channel generally designated 17. The channel comprises a chuck wall 18 merging through the inner chuck radius 19 with the central closure portion 16, and through the channel radius 20 with the seaming wall or skirt 21. The seaming wall or skirt 21 is longer than the chuck wall and is provided at its extension beyond the chuck wall depth with an inwardly turned hem 22. It will also be apparent by reference to FIGURES 2 and 6 that each can end channel also is equipped with a sealing compound or bonding adhesive as indicated at 23.

The manner of forming the closure of FIGURES 2 through 5 is progressively illustrated in said figures. It will be apparent by reference to FIGURE 2 that the lower end extremity of the can body 5 is supported and confined at 24 on the bed plate 25, and in said figure, the can end or cover is shown as having been dropped onto the upper end extremity of the body and resting on the horizontal shoulder 11, as at 26. Relative movement between the bed plate 25 and a chuck roll 27 is then brought about to place the chuck roll base 28 against the central closure portion 16 of the can end or cover and the chuck wall 29 of the roll within the chuck wall 18 of the can end, as shown in FIGURE 3. With the chuck roll thus placed, a seaming roll 30 interlocked at 31 with the chuck roll 27 in the well known manner is moved into contact with the seaming wall or skirt 21 of the can end, said seaming roll including the usual seam pressing

and conforming wall 32 and a can end seaming wall reshaping and locking portion 33. The cooperation or moving together of the seaming roll and the chuck roll serves to tightly conform the can end walls 18 and 21 and the can body wall portion 8 embraced between them in the manner clearly illustrated in FIGURE 3. The seaming wall reshaping and locking portion 33 of the seaming roll is so formed as to be effective during the rolling of the seam by the seaming roll as to first bring the hem 22 into engagement with the bead 10 as at 34 and turn the hem inwardly as at 35, and then to reshape the hem progressively to conform and lock the same under the horizontal shoulder 9 as illustrated in FIGURE 4. In the process of reshaping and locking the cover skirt reinforcing hem in the manner described, and as shown progressively in FIGURES 3 and 4, the cover channel is drawn downwardly to firmly seat the inner chuck radius 19 on the horizontal shoulder, pulling the seaming wall or skirt 21 downwardly and putting the same and holding the same in tension over the end extremity 9 of the can body wall portion 8, as shown in FIGURE 4.

It will be observed by reference to FIGURE 4 that not only is the can end or cover reinforcing hem 22 conformed to and securely locked under the bead 10 and the horizontal locking shoulder 9 thereof, but the raw metal edge of the hem is so enclosed within the seam structure as to avoid exposure thereof to the elements. In the process of forming the seam as herein described, the sealing compound or bonding agent 23 is distributed in the seam in the manner illustrated in FIGURES 3 and 4, serving to efficiently seal the seam when mere sealing compounds are employed, and to both seal and provide for an efficient bonding of the seam and its components when a bonding adhesive is employed.

In the form of the invention illustrated in FIGURES 7 through 10, can ends or covers of the form illustrated in FIGURE 10 are employed. These can ends are similar to the covers previously described except for the fact that they are equipped at the downwardly and outwardly flaring extremities of the downwardly opening channel with an outwardly and upwardly turned curl 37, rather than the inwardly turned hem structure shown in FIGURE 6. In other words, each of these modified can ends includes a central closure portion 38 surrounded by an upwardly and downwardly opening channel 39, said channel comprising a chuck wall 40 merging through an inner chuck radius 41 with the central closure portion 38, and through a channel radius 42 with a seaming wall or skirt 43, which as in the previous form, is longer than the chuck wall and is provided at its extremity or extension beyond the chuck wall depth with the beforementioned curl 37. A sealing compound or bonding adhesive 44 preferably is applied in the can end channel as illustrated in FIGURE 7.

These modified forms of can ends or covers are applied over can bodies which are identical in structure to those previously described, each including a generally cylindrical wall portion 45 at each end extremity and presenting an edge extremity 46, and each said generally cylindrical portion 45 merges through an inturned bead 47 with a horizontal seat or body shoulder 48, and each said shoulder 48 merges through an inwardly, downwardly and then outwardly turned portion 49 with the respective outwardly curved flare 50 which in turn merges into the main corrugated body portion, as previously described.

In FIGURES 7 to 9, progressive steps in the formation of the seam are shown, and it is to be understood that the lower extremity of the can body will be supported and confined in the manner previously described, and as shown in FIGURE 2.

In FIGURE 7, the can end is shown as having been dropped onto the upper end of the can body and resting on the seat or horizontal shoulder as indicated at 51. The chuck roll 52 is now brought into contact in the

manner previously described to present its base 53 against the can end central portion or countersink 38, as shown in FIGURE 8, and the chuck wall 54 of the roll within the can end chuck wall 40. The cooperating and interlocking seaming roll 55 includes a shaping wall portion 56 which is modified as necessary to provide for the progressive reshaping of the can end seaming wall and its extremity and its curl 37, as will be apparent by reference to FIGURES 8 and 9. The initial reshaping of the curl is shown at 57 in FIGURE 8, and the completed reshaping of the curl in the form of an outwardly turned reinforcing hem and the reshaping and locking of the seam under the horizontal bead shoulder 48 is shown at 58 in FIGURE 9.

It is understood that in both of the herein disclosed forms of the invention, namely that illustrated in FIGURES 2 through 5, and that illustrated in FIGURES 7 through 9, the reshaping and locking of the reinforcing hem under the horizontal shoulder 9 or 48 serves to draw the can end channel downwardly to firmly seat the chuck wall radius 19 or 41 against the horizontal shoulder and the channel radius 20 or 42 firmly against the end extremity of the can body, with the seaming wall 21 or 43 of the closure seam held in tension by the firm locking of the reinforcing hem under the horizontal shoulder of the bead in the manner stated.

The novel can body, closure and method of forming the same disclosed herein have provided very notable advantages, some of which are herein enumerated.

The employment of the flangeless body structure, also devoid of interlocked side seaming serves to provide great savings in metal.

The particular form of the body with its flangeless and generally cylindrical end portion 8 or 45 and the inwardly directed bead 12 or 49 serves to facilitate introduction of fill, and also to prevent rolling of fill portions into the seam structure with the result of the provision of faulty seams. The smoothly rolled bead serves to facilitate entry of the fill, and the raw metal edge at the end extremity of the body will serve to cut through fill tending to hang over the edge in position for interfering with the closure application.

The particular form of the seam structure provides for secure sealing and seam strength without the necessity of the interrolling of flanges. It will be apparent by reference to FIGURE 1 that the seam structures are so formed and positioned as to provide no projection outward beyond the mean body diameter. This arrangement provides for more compact storage and casing, and less damaging of the can ends by engagement of end seam against end seam.

The particular hem reinforced seam structures also provide secure shoulder means against which to anchor opening devices, either of the rotary type, or the fulcruming, end piercing type.

The ends or closures of the type shown in FIGURES 7 to 10 can be produced by a single operation employing present standard end presses, by simply designing the die to produce the end closures in the forming illustrated in FIGURES 7 and 10.

In the making of the closures of the form shown in FIGURES 2 and 6 there would be a first stamping out of the end closure, and in a second operation the bending over of the closure to form the initially hemmed edge thereon.

While preferred example disclosures of the closure, body and seam structures and the method of forming the closure have been described in detail herein it is to be understood that variations in said structures and the steps in said method may be made and practiced without departing from the invention as defined in the appended claims.

What is claimed is:

1. In a metal container, a generally cylindrical body having a generally cylindrical end portion terminating

endwise in a raw metal edge, said generally cylindrical portion merging into an inwardly turned bead presenting a horizontal shoulder in turn merging inwardly and in a direction generally axially away from said raw metal edge and into an outwardly and longitudinally flared and curving wall portion finally merging into the main generally cylindrical body, a closure having a central closure portion and a surrounding upstanding downwardly opening channel defined by an inner chuck wall connected with the central closure portion through a chuck radius and an outer seaming wall which is axially longer than the chuck wall and the generally cylindrical end portion and which is connected with the chuck wall through a channel radius, said central closure portion firmly resting on said shoulder about an annulus joining with the chuck wall through said chuck radius, with the seaming wall portion remote from the channel radius turned snugly under and locked against the body shoulder in a manner holding said seaming wall in tension and the closure firmly against said raw metal edge and on said shoulder with the generally cylindrical body end portions tightly embraced between the chuck wall and seaming wall and conforming in shape thereto and with the channel radius firmly engaged over the raw metal edge.

2. A closure structure as defined in claim 1 wherein the seaming wall portion remote from the channel radius carries a reinforcing hem which is engaged in shape conforming closure locking contact under the body shoulder.

3. A closure structure as defined in claim 1 wherein the seaming wall portion remote from the channel radius carries an inwardly turned reinforcing hem which is engaged in shape conforming closure locking contact under the body shoulder.

4. A closure structure as defined in claim 1 wherein the seaming wall portion remote from the channel radius carries an outwardly turned reinforcing hem which is engaged in shape conforming closure locking contact under the body shoulder.

5. A closure structure as defined in claim 1 wherein the seaming wall portion remote from the channel radius carries a reinforcing hem which is engaged in shape conforming closure locking contact under the body shoulder, and there also being included a seam sealing medium in the closure channel and engaging between the opposing faces of the generally cylindrical body portion the chuck wall and the seaming wall.

6. A closure structure as defined in claim 1 wherein the seaming wall portion remote from the channel radius carries a reinforcing hem which is engaged in shape conforming closure locking contact under the body shoulder, and there also being included a seam sealing and bonding adhesive in the closure channel and providing a metal to metal bond between the generally cylindrical body portion and the chuck and seaming walls between which it is embraced.

7. In a metal container, a generally cylindrical body having at each end thereof a generally cylindrical end portion terminating endwise in a raw metal edge, each said generally cylindrical portion merging into an inwardly turned bead presenting a horizontal shoulder in turn merging inwardly and in a direction generally axially away from the respective raw metal edge into an outwardly and longitudinally flared and curving wall portion finally merging into the main generally cylindrical body, a closure at one end of the container body and having a central closure portion and a surrounding upstanding downwardly opening channel defined by an inner chuck wall connected with the central closure portion through a chuck radius and an outer seaming wall which is axially longer than the chuck wall and the generally cylindrical end portion and which is connected with the chuck wall through a channel radius, said central closure portion firmly resting on said shoulder about an annulus joining with the chuck wall through said chuck radius, with the seaming wall portion remote from the channel radius

5 turned snugly under and locked against the body shoulder in a manner holding said seaming wall in tension and the closure firmly against said raw metal edge and on said shoulder with the generally cylindrical body end portion tightly embraced between the chuck wall and seaming wall and conforming in shape thereto and with the channel radius firmly engaged over the raw metal edge.

10 8. Container structure as defined in claim 7 wherein the seaming wall portion remote from the channel radius carries a reinforcing hem which is engaged in shape conforming closure locking contact under the body shoulder.

15 9. Container structure as defined in claim 7 wherein the seaming wall portion remote from the channel radius carries an inwardly turned reinforcing hem which is engaged in shape conforming closure locking contact under the body shoulder.

20 10. Container structure as defined in claim 7 wherein the seaming wall portion remote from the channel radius carries an outwardly turned reinforcing hem which is engaged in shape conforming closure locking contact under the body shoulder.

25 11. Container structure as defined in claim 9, there also being included a seam sealing medium in the closure channel and engaging between the opposing faces of the generally cylindrical body portion the chuck wall and the seaming wall.

30 12. Container structure as defined in claim 7 wherein the seaming wall portion remote from the channel radius carries a reinforcing hem which is engaged in shape conforming closure locking contact under the body shoulder, and there also being included a seam sealing and bonding adhesive in the closure channel and providing a metal to metal bond between the generally cylindrical body portion and the chuck and seaming walls between which it is embraced.

35 13. A metal closure for use on a metal container body devoid of an end flange, said closure comprising a central closure portion and a surrounding upstanding downwardly opening V-shaped channel defined by an inner chuck wall connected with the central closure portion through a chuck radius and an outer seaming wall connected with the chuck wall through a channel radius dimensioned for receiving the flangeless end extremity of a can body, said seaming wall being axially longer than the chuck wall and provided at its free edge extremity with an inwardly turned reinforcing hem serving also as means for holding closures in spaced relation when they are nest stacked.

40 14. A metal closure for use on a metal container body devoid of an end flange, said closure comprising a central closure portion and a surrounding upstanding downwardly opening V-shaped channel defined by an inner chuck wall connected with the central closure portion through a chuck radius and an outer seaming wall connected with the chuck wall through a channel radius dimensioned for receiving the flangeless end extremity of a can body, said seaming wall being longer than the chuck wall and provided at its free edge extremity with an inwardly turned reinforcing hem, and said channel being provided with a sealing medium in and adjacent the channel radius in position for being out of contact with a like closure nested in the closure with its seaming wall within and in contact with the inwardly turned hem of the closure.

45 15. In a metal container, a generally cylindrical body having a generally cylindrical end portion terminating endwise in a raw metal edge, said generally cylindrical portion merging into an inwardly turned bead presenting a horizontal shoulder in turn merging inwardly and in a direction generally axially away from said raw metal edge and into an outwardly and longitudinally flared and curving wall portion finally merging into the main generally cylindrical body, a closure having a central closure portion and a surrounding upstanding downwardly opening channel defined by an inner chuck wall connected

with the central closure portion through a chuck radius and an outer seaming wall which is axially longer than the chuck wall and the generally cylindrical end portion and which is connected with the chuck wall through a channel radius, said central closure portion firmly resting on said shoulder about an annulus joining with the chuck wall through said chuck radius, with the seaming wall portion remote from the channel radius turned snugly under and locked against the body shoulder in a manner holding said seaming wall in tension and the closure firmly against said raw metal edge and on said shoulder with the generally cylindrical body end portions tightly embraced between the chuck wall and seaming wall and conforming in shape thereto and with the channel radius firmly engaged over the raw metal edge, said container body being formed of metal having a thickness of 0.004 to 0.011 inch and of uniform thickness throughout the full circumference of its cross section, and the body portion intermediate the flares being uniformly and circumferentially corrugated.

16. In a metal container, a generally cylindrical body having at each end thereof a generally cylindrical end portion terminating endwise in a raw metal edge, each said generally cylindrical portion merging into an inwardly turned bead presenting a horizontal shoulder in turn merging inwardly and in a direction generally axially away from the respective raw metal edge into an outwardly and longitudinally flared and curving wall portion finally merging into the main generally cylindrical body, a closure at one end of the container body and having a central closure portion and a surrounding upstanding downwardly opening channel defined by an inner chuck wall connected with the central closure portion through a chuck radius and an outer seaming wall which is axially longer than the chuck wall and the generally cylindrical end portion and which is connected with the chuck wall through a channel radius, said central closure portion firmly resting on said shoulder about an annulus joining with the chuck wall through said chuck radius, with the seaming wall portion remote from the channel radius

10

5 turned snugly under and locked against the body shoulder in a manner holding said seaming wall in tension and the closure firmly against said raw metal edge and on said shoulder with the generally cylindrical body end portion tightly embraced between the chuck wall and seaming wall and conforming in shape thereto and with the channel radius firmly engaged over the raw metal edge, said container body being formed of metal having a uniform thickness of 0.004 to 0.011 inch and being of uniform thickness throughout the full circumference of its cross section, the body portion intermediate the flares being uniformly and circumferentially corrugated.
